UNITED STATES PATENT OFFICE.

CARL H. DUEDE, OF STUART, IOWA.

DESIGN FOR AN AEROPLANE-COASTER.

56,803.

Specification for Design.

Patented Dec. 28, 1920.

Application filed May 5, 1920. Serial No. 379,145. Term of patent 14 years.

To all whom it may concern:

Be it known that I, CARL H. DUEDE, a citizen of the United States, residing at Stuart, in the county of Guthrie and State of Iowa, have invented a new, original, and ornamental Design for an Aeroplane-Coaster, of which the following is a specification, reference being had to the accompanying drawing, forming part thereof.

Figure 1 is a side elevational view, and

Fig. 2 is a top plan view of the aeroplane coaster showing my new design.

I claim:

The ornamental design for an aeroplane coaster, as shown.

CARL H. DUEDE.
